(57) **CLAIM**

The ornamental design for a bottle, as shown and described.

DESCRIPTION

FIG. 1 is a perspective view of a bottle, showing the top, a side and the front of our new design;

FIG. 2 is a front elevational view of the bottle;

FIG. 3 is a back elevational view of the bottle;

FIG. 4 is a right side elevational view of the bottle;

FIG. 5 is a left side elevational view of the bottle;

FIG. 6 is a top plan view of the bottle; and,

FIG. 7 is a bottom plan view of the bottle.

In all views, an optional pump dispenser is present in outline form; the pump dispenser is shown to illustrate a use of the bottle and forms no part of the claimed design.
